UNITED STATES PATENT OFFICE.

EDWARD J. TRIAY, JR., OF JACKSONVILLE, FLORIDA.

LACE-LOCKING MEANS FOR ARTICLES OF PERSONAL WEAR.

Application filed January 14, 1922. Serial No. 529,242.

To all whom it may concern:

Be it known that I, EDWARD J. TRIAY, Jr., a citizen of the United States, a resident of Jacksonville, in the county of Duval and 5 State of Florida, have invented certain new and useful Improvements in Lace-Locking Means for Articles of Personal Wear, of which the following is a specification.

In many articles of personal wear, such as 10 shoes, corsets and the like, including surgical bandages, it is frequently necessary, or desirable, to bring the lacing edges closer together in certain zones than in other zones.

It has been the custom, in connection with 15 corsets, for the wearer to tie knots in the lacing string so as to hold the lacing edges at a predetermined juxtaposition so that a given pressure or shape is maintained within that zone irrespective of the other zones of 20 the lacing edges.

In the case of shoes equipped with my invention, the use of arch supports and the like may be eliminated inasmuch as the shoe may be drawn to a snug fit around the foot and 25 this fit maintained at all times while the shoe is on the foot; while the lacing in other zones may be comparatively loose.

Frequently in the case of surgical bandages, it is desirable to have certain zones of 30 the bandage much tighter than other zones. This can be readily and efficiently accomplished by my invention.

My invention may be efficiently used in connection with many other articles.

35 The object of my invention is to provide a lacing edge with means whereby said edge can be drawn much tighter in certain zones than in others without affecting the pliability of adjacent edges in other zones in the 40 same article.

My invention consists of a lacing edge provided throughout its entire length or in predetermined zones with means for locking the lacing string against movement after 45 said string is once adjusted in a given lacing eyelet.

In the drawings:

Figure 1 is a detailed view of a portion of a shoe showing my invention applied thereto;

50 Fig. 2 is a similar view of a corset;

Fig. 3 is a side elevation of Figure 4;

Fig. 4 is a top plan view of one of the locking eyelets.

Fig. 5 is a top plan view of the eyelet embodied in my invention.

Fig. 6 is a side elevation of Figure 5.

Fig. 7 is a vertical transverse section of Figure 5.

Fig. 8 is a rear elevation of Figure 5.

While I have selected certain articles of 60 wearing apparel for the purpose of illustrating my invention, it will, of course, be understood that my invention is susceptible of efficient use with many other articles of personal wear as well as surgical bandages. 65

Reference numeral 1 is a shoe having the lacing edge 2 provided with eyelets. The eyelets shown in Fig. 1 consist of the construction shown in Figs. 4, and 5 to 8.

In Fig. 4 the eyelet 3 comprises a main 70 body having an angular groove 4 within which the material of the lacing edge is adapted to be clamped.

The eyelet 3 is provided with a lacing 75 string lock offset, which offset, as shown in Fig. 4, is substantially V-shaped in construction, so that when a lacing string is pulled firmly within the lock offset 5, the lacing string 6 is crowded into the lock offset and wedged therein against sliding 80 movement through the eyelet.

In numerous instances, it is necessary, or desirable, to draw the edges of the lacing 85 strips 2 very closely together in the proximity of the instep of the foot, and maintain them in that position while the shoe is in use. It is impossible to do this with the present construction of eyelet

provided in shoes, and in the effort to do it the shoe is uncomfortably tightly laced 90 around other portions of the foot and ankle, whereas by the use of my invention the lacing edge 2 may be brought closely together at the lower zone of the lacing edges and when in that position the lacing 95 string 6 is tightly wedged within the lock offset 5 of the eyelet 3, and locked against relative movement through the eyelet; whereby a predetermined position of

proximity of the lacing edges within that or 100 any other zone is maintained. This possible adjustment of the lacing edges enables one to draw the shoe snugly around the foot, thereby supporting the foot and making it possible for one to discard the use of the 105

usual so-called arch supports, because the shoe can thus be maintained in this predetermined close fit as a support for the arch of the foot.

To meet the wishes of those who may desire to use what is known as hook eyelets for shoes, I have designed the construction of eye-

let shown in Figures 5 to 8, both inclusive; and in this construction the eyelet is provided with the base 7 having an angular groove 8, within which the material of the shoe is clamped and a hook 9 which may be provided with a depending wedging edge 10, which functions like the wedging offset 5 of the eyelet 3.

This locking edge 10 may be formed by 10 depressing the material of the hook 9 as clearly shown in Figures 5, 6, 7, and 8.

Referring to Fig. 2, it will be noted that I have shown a corset provided with my improved eyelets 3 and the usual round eyelet 11 so that the lacing edges of the corset provided with the eyelets 3 may be adjusted to their desired juxtaposition, and the lace 12 may be firmly locked within the locking recess 5 of the eyelet 3, thereby maintaining 15 the adjusted relative position of the lacing edges while the lace 12 may be free to move through the eyelets 11 to accommodate body movements, but, at the same time, the lace in the eyelet 3 is held against movement relative to the eyelet.

What I claim is:

1. In an article of personal wear, having free edges adapted to be secured together, of a series of eyelets arranged along said free edges at predetermined intervals, said eyelets each having a locking offset at one side, positioned between said edge and the other side of the eyelet; said offset constructed to

receive and lock a lacing string against movement after the proper tension has been placed on the string to hold the said free edges at the desired distance apart in any selected zone throughout the length of the said free edges.

2. In an article of personal wear having free edges adapted to be secured in proximity to each other, of a series of eyelets arranged along said free edges, said eyelets each having a lace locking member at one side positioned near the said free edges; 40 said offset being constructed to receive and lock a lacing string against movement after the desired tension has been placed on the string to hold the said free edges at the desired distance apart in any selected zone at 45 intervals or throughout the length of the said free edges.

3. In an article of personal wear having free edges adapted to be secured in proximity to each other, of a series of round eyelets arranged along said free edges in groups, and a series of eyelets also arranged along said free edge and having a lace locking member whereby the desired tension may be placed upon and retained by the 50 lacing string to hold the free edges at the desired distance apart in selected zones at 55 intervals throughout the length of said free edges.

In testimony whereof I affix my signature. 60
EDWARD J. TRIAY, JR.
